MEANS FOR GENERATING TIME MODULATED ELECTRICAL PULSES

Maurice Moise Levy, London, England, assignor, by mesne assignments, to International Standard Electric Corporation, New York, N. Y., a corporation of Delaware

Application May 30, 1944, Serial No. 538,061
In Great Britain June 1, 1943

5 Claims. (Cl. 332—14)

1

The present invention relates to arrangements for deriving a phase-modulated train of short electrical pulses from a modulated carrier wave.

A train of pulses is phase-modulated when the time interval between successive pulses is varied according to the modulating signal, the duration or form of the pulses remaining unaltered.

The principal object of the invention is to provide a simple method of obtaining a phase-modulated train of pulses directly from a modulated carrier wave without an intermediate demodulation. The arrangements are substantially the same whether the carrier wave is amplitude-, frequency-, or phase-modulated.

According to the invention there is provided an arrangement for obtaining a phase-modulated train of short electrical pulses, comprising a source of a signal modulated sinusoidal carrier wave, means for generating a train of pulses, and means for applying the carrier wave to synchronise the generating means in such a manner that the time spacing of the generated pulses varies in accordance with the modulating signal.

According to another aspect, the invention consists in an arrangement for phase-modulating a train of short electrical pulses in accordance with a signal, comprising means for generating a sinusoidal carrier wave, means for modulating the wave by the signal, means for generating a train of pulses, and means for applying the modulated carrier wave to control the times of emission of the pulses in such a manner that the interval between successive pulses varies in accordance with the signal amplitude.

According to a further aspect, the invention provides an arrangement for deriving a phase-modulated train of short electrical pulses from an amplitude-modulated sinusoidal carrier wave comprising pulse generating means connected to the source of the carrier wave and means for causing the carrier wave to synchronise the pulses in such a manner that the time at which any pulse is emitted is a function of the instantaneous amplitude of the modulating signal at that time.

The invention will be described with reference to the accompanying drawings in which:

Fig. 1 is a diagram used to explain a preferred synchronising arrangement employed in the present invention;

Fig. 2 shows a schematic circuit diagram of a pulse generating arrangement embodying the present invention;

2

Fig. 3 gives diagrams used in explaining the action of the system of Fig. 2;

Fig. 4 is a diagram used to explain the action of the system of Fig. 5;

Fig. 5 shows a schematic circuit diagram of a multivibrator synchronised according to a preferred arrangement; and

Fig. 6 is a diagram used to explain the action of Fig. 5.

10 The invention employs pulse generating arrangements which are adapted to be synchronised by a controlling wave, preferably, though not necessarily, by the methods described in the specification of copending application Ser. No. 15 526,605, filed March 15, 1944, now Patent No. 2,462,109, issued February 22, 1949.

The invention described in the above-quoted specification is concerned with pulse generators and improving the stability of the synchronisation on a submultiple of the controlling frequency. Fig. 1 shows the method adopted.

Short duration unidirectional pulses are derived from saw-tooth waves and are delayed and mixed with a control wave. The sign of the 25 pulses is chosen so that they momentarily reduce the negative bias applied to the control grid of the pulse generator valve. The effect of the striking voltage curve is shown in Fig. 1. It will be seen that the pulses depress every tenth loop 30 of the control wave so that the upward slope of the saw-tooth wave can make contact therewith. If the amplitude of the synchronising pulses is chosen so that contact is made not far from the centre of the flank of the controlling wave as shown, then considerable variation of the operating voltage or amplitude of the controlling wave is allowable before control is lost, and the adjacent loop of the control wave is out of the way and therefore cannot intercept the 35 saw-tooth curve.

As will be explained later, the pulse which causes the discharge of the condenser C_1 in Fig. 2, thereby producing the fly-back stroke, is derived after a definite delay from the preceding 45 fly-back stroke of the saw-tooth wave. So long as the delay is approximately correct, the desired result will be obtained, and errors in the time spacing of the pulses do not accumulate.

Fig. 2 shows one arrangement in which the synchronising is carried out by the method described with reference to Fig. 1. The circuit for producing the saw-tooth waves comprises a gas-filled valve V_1 arranged as a relaxation oscillator periodically discharging condenser C_1 which is 55 charged via resistor R_1 by the high tension source

HT. The valve V_2 is arranged as a simple pulse generator which is excited by the saw-tooth waves obtained through condenser C_2 from a tapping on the resistance R_1 . The control grid of V_2 is connected to the cathode through two series resistances R_2 and R_3 and a battery or other source B_3 adapted to apply a positive potential to the control grid. The resistance R_3 should be a relatively high resistance adapted to ensure that the positive grid potential is small.

The point on R_1 to which the condenser C_2 is connected should be chosen so that the sudden reduction in the voltage applied to the control grid of V_2 which occurs at the fly back stroke of the saw-tooth wave is sufficient to block the valve. The condenser C_2 becomes charged at the same time, and discharges through the resistance R_2 and the lower portion R_5 of R_1 . If the time constant $C_2(R_2+R_5)$ is small compared with the time constant C_1R_1 of the relaxation circuit, then the potential of the grid of V_2 will quickly rise until the valve is unblocked and anode current begins again to flow. Thus the anode potential of V_2 suddenly rises to a maximum on the occurrence of the fly-back stroke, and then remains constant for a short period determined by the time constant $C_2(R_2+R_5)$ and then falls to the original value again, producing very nearly rectangular pulses across the anode resistance R_4 . In Fig. 6 curve *a* shows the saw-tooth waves and *b* the voltage pulses obtained across the resistance R_4 . These pulses are applied through a blocking condenser C_3 to the input terminals of a delay network DN, the output terminals of which are terminated with a resistance R_6 . The upper terminal of R_5 is connected by the conductor *x* back to the control grid of the valve V_1 through the biasing battery B_2 and the secondary winding of the transformer T .

Delayed pulses will be obtained at the output of DN as shown in Fig. 3, curve *c*. The n th pulse of *c* is delayed with respect to the n th pulse of *b* by a time T_1 which is very slightly shorter than the desired period T of the saw-tooth waves, so that the $(n+1)$ th fly-back stroke of the saw-tooth wave occurs approximately at the centre of the n th delayed pulse. The delay T_1 can be obtained by appropriate design of the delay network DN.

The duration of the pulses *b* and *c* can be controlled by adjusting the time constant

$$C_2(R_2+R_5)$$

which may be done by varying any or all of the components C_2 , R_2 and R_5 .

It should be mentioned that the battery B_3 is not essential and may be omitted. The circuit will operate in this case in very nearly the same way; the grid of V_2 will, however, be slightly negative instead of slightly positive in the intervals between the pulses.

One preferred form of the delay network DN consists of an artificial non-dissipative transmission line which may be made up of a number of low-pass filter sections, comprising series inductances and shunt condensers, adjacent inductances being preferably mutually coupled. The sections should be chosen to be sufficiently short so that a high cut-off frequency is obtained, in order not appreciably to deform the pulses. Such an artificial line is very convenient because the delay is substantially independent of frequency over a wide range, and if means is provided for tapping off at any section of the filter, a delay adjustable over a wide range may be ob-

5 tained. If such a delay network is used, the resistances R_4 and R_5 should be adjusted so that the network is terminated at both ends by its characteristic impedance, in order to avoid reflections of the pulses at the terminals.

The pulses generated by the methods already described will be slightly trapezoidal in form on account of the slope of the trailing edges resulting from the discharge curve of the condenser C_2 .
10 By a slight modification of the arrangement of Fig. 2, truly rectangular pulses can be obtained. In this modification the conductor *x* is removed, and the connection back to the control grid of V_1 is taken instead through the connection *y* to an adjustable tap *t* at some intermediate point of the delay network DN. The resistance R_5 should also be short-circuited. The grid battery or other source B_3 should preferably in this case bias the grid negatively.

15 The time constant $C_2(R_2+R_5)$ should be adjusted to be rather larger than before, so that the duration of the pulses generated by the valve V_2 is not much smaller than the period of the saw-tooth wave. Such pulses are shown at *d* in Fig. 25. These pulses are transmitted through the delay network DN and reach the tap *t* after a time T_1 slightly less than the period of the saw-tooth wave, as shown at *e*. The pulses continue to the short circuited end, where they are reflected with 30 an inversion and return to the tap *t* after a further short period T_2 , as shown at *f*. They continue back to the input end of the delay network where they are absorbed without reflection, the network being properly terminated by R_4 as already explained.

35 Curve *g* of Fig. 3 shows the resultant effect at the tap *t*. Short rectangular upwardly directed pulses are obtained by the superposition of the two series of pulses *e* and *f*, each pulse being preceded by a downwardly directed V-shaped pulse. This latter pulse could be removed by amplitude limitation or in any other way if desired, but its presence is not harmful, since the effect will be only to raise momentarily the striking voltage of the valve V_1 at a time when it is not required to strike.

45 It will be evident from the above explanation that the duration T_2 desired for the pulses is obtained by arranging the tap *t* at a distance from the short-circuited end corresponding to $T_2/2$. The delay period T_1 which will be approximately equal to $T-T_2/2$ gives the distance between the input terminals of the network and the tap *t*. In practice it will be found convenient to provide an adjustable short-circuiting switch (not shown) by which the network may be short-circuited at any desired intermediate point. By this means both the times T_1 and T_2 can easily be selected for a variety of conditions.

50 In Fig. 2 an output terminal 6 is provided from which the synchronised pulses may be obtained.

The same principles may also be applied to synchronising a multivibrator circuit on a sub-multiple of the controlling frequency. In Fig. 5 is shown one well known form of a multivibrator comprising two valves V_3 and V_4 having their control grids and anodes cross-connected through condenser-resistance circuits C_7 , R_7 and C_8 , R_8 . The resistances P are appropriate anode current supply resistances, and the grids are negatively biased by suitable means represented by batteries B_5 and B_6 . The properties of this circuit are explained in detail in the specification of application Ser. No. 445,510 filed June 2, 1942, now

Patent No. 2,436,808, but its action will be briefly described here.

The valves V_3 and V_4 are alternately cut-off and saturated for periods determined by the time constants C_7R_7 and C_8R_8 . Thus the grid voltage of V_3 remains below the cut-off point for a short period, determined by the time constant C_7R_7 , during which the anode voltage remains substantially constant at a maximum value. During this period the grid voltage of V_4 is above the saturation point, so that the anode voltage remains substantially constant at a minimum value. At the end of this period the grid voltage of V_3 reaches the cut-off point, and the condition suddenly changes over so that V_3 is now saturated and the grid voltage of V_4 is taken below the cut-off point. This condition persists for a longer period determined by the time constant C_8R_8 , during which the grid voltage of V_4 rises to the cut-off point, on which the condition suddenly changes back again and the cycle is repeated. Thus it will be seen that positive short duration voltage pulses are generated at the anode of V_3 and inverted pulses of similar duration are generated at the anode of V_4 .

Fig. 4 shows the time variation of the grid voltage of the valve V_4 . In this figure the dotted line V_c indicates the cut-off voltage, and the dotted line V_a the saturation voltage.

The emission of a pulse is determined when the grid voltage reaches the line V_c , on which it suddenly rises above the line V_a as shown at a . It then falls, following the curve b which is determined by the discharge of the condenser C_7 , and then drops suddenly below the cut off at c , this taking place at the moment of unblocking of the valve V_3 . The grid voltage then rises rather slowly, following the curve d determined by the discharge of the condenser C_8 , until the line V_c is again reached, when the process is repeated. In order to obtain rectangular pulses at the anode of V_4 it is necessary to arrange that the curve b does not reach the line V_a before the circuit changes over.

The frequency of repetition of the pulses is determined by the curve d which in turn depends on the time constant C_8R_8 . It will be evident that the time at which the curve d reaches the line V_c will be very sensitive to small changes in V_c or in the values of C_8 and R_8 , so that the arrangement is found to be very unstable and irregular in operation.

The arrangement of Fig. 5 may be synchronised on the frequency of a controlling sinusoidal wave, or on a submultiple, by supplying the wave in series with the resistance R_s , so that the vertical strokes a (Fig. 4) occur at times determined substantially by the controlling wave, the curve d merely deciding which submultiple is to be employed. As in the case of Fig. 2, the synchronising becomes rather unstable for submultiples of high order, and it is therefore preferable to employ synchronising pulses in the manner shown in Fig. 5.

Connected in series with the resistance R_s (which is the one which is concerned in defining the frequency of repetition) is the secondary winding of a transformer T through which the controlling wave is applied, and a resistance R_s shunted by two delay networks DN_1 and DN_2 . These networks are used for generating synchronising pulses which operate similarly to those previously described. Ignoring these pulses for the moment, it will be understood that the synchronising wave will be superposed as "ripples"

on the curve of Fig. 4, and every third ripple, for example, will cross the line V_c , thereby determining the time at which the next pulse is emitted. Since, however, the slope of the curve d is so small, the arrangement will be unstable for submultiples of high order as already stated. If, however, the synchronising ripple is superposed on the top of a pulse, it will be raised up out of the way of the preceding ripples and the arrangement becomes stable. This can be seen from Fig. 6 which shows to an enlarged scale part of Fig. 4 when the synchronising wave and pulse are supplied. In Fig. 6, the full line represents the actual variation of the grid voltage.

The negative grid bias voltage produced by B_s is first of all increased, so that the dotted discharge curve d would occupy the position shown in the absence of the synchronising waves. The leading edge f of the synchronising pulse is timed to occur slightly before the time when the generated pulse is emitted, and its duration should be about equal to one period of the synchronising wave. One loop of the wave is thus raised up so that it cuts the line V_c causing the generated pulse to be emitted. The leading edge of this pulse is shown at a .

The synchronising pulse for the $(n+1)$ th pulse of Fig. 4 is obtained from the n th pulse by reflection in the delay network DN_1 whose output terminals are left open as shown. In this way the n th pulse which is generated across the resistance R_s , is reflected back without an inversion, as desired. The total delay suffered by the reflected pulse in DN_1 should be a little less than the repetition period T desired for the generated pulses. The network DN_2 has its output terminals short-circuited in order to obtain an inverted reflected pulse delayed slightly longer than the pulse reflected in DN_1 , so that the combination of the two reflected pulses may produce a short synchronising pulse in a manner similar to that described with reference to the curves d to g of Fig. 3. If the duration of the synchronising pulse is to be T_2 , then network DN_2 should delay the reflected pulse by a total time which is greater by T_2 than the total delay in DN_1 . Alternatively, the delay network DN_2 may be arranged to delay the reflected pulse by a total time equal to T_2 . Thus, when a pulse appears across the resistance R_s , the network DN_2 produces a synchronising pulse having the required duration T_2 which pulse is then delayed by the desired amount in the network DN_1 in the manner explained.

It may be added that the network DN_2 is not essential and can be omitted, in which case the synchronising pulse will have the same duration as the emitted pulse. This will operate satisfactorily since the synchronising pulse will have disappeared before the emitted pulse is due to disappear.

It is to be noted that the resistance R_s should be chosen so that the networks are correctly terminated, in order to avoid any further reflections of the pulses at the input terminals of the networks.

Reference will again be made to Fig. 2. Let an amplitude modulated carrier wave be applied as a controlling wave to the terminals 1 and 2 instead of the usual simple sinusoidal wave. The effect will be that in Fig. 1 the amplitude of the wave 4 will vary. When the amplitude increases the fly-back stroke will occur a little earlier than usual, and when it decreases it will occur a little later.

The use of synchronising pulses has another advantage. From Fig. 1 it can be seen that the synchronising point can be arranged anywhere on the descending flank of the loop, by suitably choosing the amplitude of the synchronising pulse. Of course, if the synchronising point be chosen exactly at the centre of the flank of the loop, the phase modulation of the generated pulses will be zero since this point is not shifted by the amplitude modulation, but if any other point on the substantially straight part of the flank be chosen, not too far from the centre, the phase modulation of the pulses will not suffer appreciable distortion.

It will be evident from what has been said that the multivibrator circuit of Fig. 5 may also be made to generate phase-modulated pulses by supplying an amplitude-modulated carrier wave, the modulated carrier wave being supplied to the terminals 1 and 2, the amplitude of the synchronising pulse being so chosen that the flank of the synchronising loop of the control wave intersects the line V_c at some point other than the centre.

In the above explanation it has been assumed that the controlling wave is amplitude-modulated. It will be obvious that the arrangement will also operate if the controlling wave is phase- or frequency-modulated. In that case, the amplitude remains constant but the loops are shifted sideways by the modulation, some coming sooner and others later than usual. It will be evident that the saw-tooth waves and the pulses derived from them will be phase modulated accordingly. The preferred arrangement shown in Fig. 1 in which synchronising pulses are used also operates satisfactorily, since although the synchronising pulses will not now generally register accurately with the synchronising loops, this is not of much importance as only approximate registration is necessary. Similar remarks apply to the arrangement of Fig. 5.

The principles on which the invention is based have been explained with reference to certain specified circuit arrangements which, however, do not represent every possible arrangement. In essentials the invention comprises a source of a modulated carrier wave connected to a pulse generator so that the carrier wave controls or synchronises the generated pulses, so that they are phase-modulated in accordance with the original modulating signal.

The source of the carrier wave may be, for example, a transmission channel of any kind conveying the modulated wave from a distant point in the usual way. It may, however, be a convenient modulating arrangement comprising, for example, a modulator supplied simultaneously with a signal wave and a locally generated carrier wave, in which case the arrangement of the invention provides a means for phase-modulating a pulse train with the signal wave.

Preferably, synchronising pulses are combined with the modulated carrier wave in order to improve the stability of the arrangement, and to enable the conditions to be chosen so that the

modulation of the pulses is substantially free from distortion, as explained.

What is claimed is:

1. An arrangement for phase-modulating a train of short electrical pulses in accordance with a signal, comprising means for generating a sinusoidal carrier wave, means for amplitude modulating the wave by the signal, means for generating a train of pulses, means for synchronizing the generation of the train of pulses on a submultiple of the carrier frequency means for applying the modulated carrier wave to said generating means to control the times of emission of the pulses in such a manner that the interval between successive pulses varies in accordance with the signal amplitude, means for deriving synchronizing pulses from the pulse generating means and means for applying the synchronizing pulses in conjunction with the carrier wave to the pulse generating means for synchronizing the pulse train.
2. An arrangement according to claim 1 in which the pulse generating means comprises a relaxation oscillator for generating waves of a saw-tooth type and means for deriving substantially rectangular pulses from the saw-tooth waves.
3. An arrangement according to claim 1 in which the pulse generating means comprises a multivibrator adapted to generate substantially rectangular pulses directly.
4. An arrangement according to claim 1 including a delay network for deriving the synchronizing pulses from the pulse generating means.
5. An arrangement according to claim 1 in which the pulse generating means includes a relaxation oscillator for generating saw-tooth waves, said oscillator comprising a gas filled triode arranged periodically to discharge a condenser, means to derive from the saw-tooth waves themselves a train of uni-directional pulses repeated at a sub-multiple of said carrier wave frequency, a delay network for delaying the said synchronizing pulses by a time interval slightly shorter than the period of the saw-tooth wave, and means to apply the pulses from the delay network in conjunction with the modulated carrier wave to the control grid of said triode.
